UNITED STATES PATENT OFFICE.

EDWARD F. DUDLEY, OF OAK PARK, ILLINOIS, ASSIGNOR TO MIEHLE PRINTING PRESS
& MFG. CO., OF CHICAGO, ILLINOIS, A CORPORATION OF ILLINOIS.

GRIPPER-GUIDE ARRANGEMENT.

Application filed March 24, 1922. Serial No. 546,325.

To all whom it may concern:

Be it known that I, EDWARD F. DUDLEY, a citizen of the United States, residing at Oak Park, in the county of Cook and State 5 of Illinois, have invented certain new and useful Improvements in Gripper-Guide Arrangements, of which the following is a specification.

This invention relates to printing presses 10 and more particularly to cylinder gripper guide mechanism.

In registering a sheet of paper it is a well known fact that a sheet can be registered more accurately by what is known as point 15 register as distinguished from line register. For example, if the registering edge of a sheet of paper to be registered is not cut perfectly straight, it is apparent that it would be quite impossible to register such 20 sheet accurately by line register, that is, by having such irregular edge of a sheet engage a large number of register members arranged in a straight line. On the other hand, however, such sheet even though the 25 edge to be registered were irregular, could be registered by point register, that is, registered at two points.

Accordingly, one object of this invention is to provide simple and efficient gripper 30 mechanism whereby sheets of material may be point registered.

Any other object is to provide gripper means whereby various grippers may be selectively used for point registering sheets of 35 material varying in dimensions.

Another object is to provide point register gripper mechanism simple and efficient in operation and adapted to meet the various requirements for successful commercial use.

40 These and other objects are accomplished by means of the arrangement disclosed on the accompanying sheet of drawings, in which—

Figure 1 is a transverse sectional view of 45 a printing cylinder embodying my invention;

Figure 2 is a fragmentary sectional view taken in the plane of line 2—2 of Figure 1;

Figure 3 is an enlarged perspective view 50 of one of my improved cylinder grippers;

Figure 4 is a reduced schematic view showing the grippers in plan view and a sheet selectively point registered with respect to two of said grippers; and

55 Figures 5, 6 and 7 are top plan, front ele-

vational and bottom plan views respectively of a modified form of gripper.

The various novel features of my invention will be apparent from the following description and drawings, and will be particularly pointed out in the appended claims.

Referring to the figures of the drawings, it will be noted that my invention is disclosed in connection with a printing press 60 cylinder 10, which carries a plurality of grippers, each having a gripper head 11 and a shank 12, said grippers being opened by any suitable mechanism 13 including arms 14 which engage the lower ends of the grippers, and closed by coiled springs 15 coiled around the shanks 12 of said grippers. Such coiled springs 15 and the shanks 12 of the grippers are housed in the gripper bar 16, between the upper edge 17 of which and the 70 gripper heads 11 sheet material fed to the cylinder is gripped.

Heretofore the sheet engaging portions of the shanks of the grippers have been round and such round outer sheet engaging surfaces of the shanks have been the same distance radially outwardly from the longitudinal center of such shanks. Accordingly, where three or more grippers have been used, all registration, of necessity, had to 80 be line registration as distinguished from point registration mentioned hereinabove.

To overcome the disadvantageous features mentioned in connection with line registration, I have provided each shank 12 directly 85 below the gripper head 11 with a flattened portion 18 which extends radially inwardly beyond points on the rounded portion of the shank. Accordingly, with the use of

such grippers, it is apparent that point registration may be effected by presenting the rounded portion of only two of the gripper shanks to the sheet to be registered, the flattened portions 18 of all of the other gripper shanks 12 being presented but not being 90 engaged by the sheet of paper being registered.

Referring particularly to Figure 4 of the drawings, it will be noted that I have shown eleven grippers in elevation, with only two 105 of the grippers 19 and 20 being used for front registering the sheet 21. In other words, the rounded portions of shanks 19 and 20 are presented to and engaged by the front edge of the sheet 21 being regis- 110

tered. The shanks of all of the other grippers are presenting their flattened faces 18 to the sheet, but it will be noted that the sheet does not engage such flattened portions. In this connection, attention is called to the fact that each of the grippers is rotatably mounted and its lower end 22 is flattened and wedge-shaped and fits into a correspondingly shaped recess 23 in its associated supporting and actuating member 14. Accordingly, each gripper may occupy one of two positions 180 degrees apart with respect to its associated member 14. In one position it presents its rounded face to a sheet of paper to be registered and in the other position it presents its flat surface 18. For rotating the grippers the head 11 of each is provided with a slot or groove 24 for the reception of a screw driver. Only sufficient force need be applied through the screw driver to the grippers to overcome the springs 15 in rotating the grippers from one position to another. As a matter of convenience, the heads of the grippers are provided with arrows indicating the rounded sheet engaging portions of the shanks.

In Figures 5, 6 and 7 I have shown a modified form of gripper in which the shank 25 in each case has three points 26, 27 and 28 of register at different distances from the longitudinal center of the shank, such points preferably being angularly spaced 90 degrees apart, whereby the line of front register may be changed. Each shank also has the flat part 29 which is presented when the gripper is not to be used actively in front registering a sheet of material. The lower end of each shank 25 is wedge-shaped and flattened on four sides so that the grippers 40 may be yieldably held in place at each 90 degrees of rotation thereof.

By means of this arrangement the grippers may be selectively chosen and moved from one position to another to accommodate any sized sheet of paper within the range of the press, provision being made at all times for point registering the sheet material as distinguished from line registering.

It is my intention to cover all modifications of the invention falling within the spirit and scope of the following claims.

I claim:

1. In a printing press, a cylinder having rotatably mounted grippers carried thereby, said grippers having gripping heads and shanks therebelow, said shanks having sheet engaging portions extending radially beyond other portions in the same transverse plane whereby said grippers may be selectively used for point registering sheet material.

2. In a printing press, movably mounted grippers having gripping heads and shanks

therebelow, said shanks having sheet engaging portions extending radially beyond other portions whereby said grippers may be selectively used for point registering sheet material.

3. In a printing press, movably mounted grippers, said grippers having gripping heads and shanks therebelow, said shanks having sheet engaging portions extending radially beyond other portions whereby said grippers may be selectively used for point registering sheet material, and means for releasably locking said grippers in different positions.

4. In a printing press, movably mounted grippers having gripping heads and shanks, means for engaging said shanks for releasably holding same in different positions with respect thereto, said shanks having sheet engaging portions extending radially beyond other portions thereof whereby said grippers may be selectively used for point registering sheet material.

5. In a printing press, a cylinder having rotatably mounted grippers carried thereby, said grippers having gripping heads and shanks therebelow, said shanks having sheet engaging portions extending radially beyond other portions in the same transverse plane whereby said grippers may be selectively used for point registering sheet material, said head having means whereby the latter may be engaged by a tool for rotation.

6. In a printing press, movably mounted grippers having gripping heads and shanks therebelow, said shanks having sheet engaging portions extending radially beyond other portions whereby said grippers may be selectively used for point registering sheet material, said grippers having indicating means for indicating the positions of said grippers to indicate the operative positions thereof.

7. A gripper for a printing press including a gripper head and a shank, said shank having portions located at different distances from the longitudinal center thereof whereby said gripper may be effective or not in point registering.

8. A gripper for printing presses including a gripper head and a rounded shank, the latter of which is provided with a flat portion whereby said gripper may be effective or not in point registering.

9. A gripper for a printing press including a gripper head and a shank, said shank having portions located at different distances from the longitudinal center thereof whereby the line of register may be changed.

Signed at Chicago, Illinois, this 21st day of March, 1922.

EDWARD F. DUDLEY.
